UNITED STATES PATENT OFFICE.

EDWARD R. HEWITT, OF RINGWOOD, NEW JERSEY.

PISTON.

1,115,535.

Specification of Letters Patent.

Patented Nov. 3, 1914.

Application filed February 9, 1912. Serial No. 676,610.

To all whom it may concern:

Be it known that I, EDWARD R. HEWITT, a citizen of the United States, resident of Ringwood, in the county of Passaic, State 5 of New Jersey, have invented certain new and useful Improvements in Pistons, of which the following is a specification, reference being had to the accompanying drawings, forming a part hereof.

10 This invention pertains to pistons, and more particularly such as are used in internal combustion engines, and has for its object features of construction of the piston to improve the operation and particularly 15 certain conditions of lubrication of the engine.

The application of my invention may be on other forms of engines or under other conditions, and may be modified from what 20 I hereafter specifically describe and show in the accompanying drawings in which a specific embodiment is illustrated.

The drawing shows an engine of simple construction in vertical section, showing the 25 piston partly broken away.

In the drawing, A is a cylinder; B a piston; C a crank case; D piston packing rings; E piston oil ring; F annular oil recess and F' another annular oil recess; G 30 indicates oil holes, G' other oil holes in the piston.

In the usual four-cycle engine operation, the engine, as shown, is lubricated in the usual manner so that the walls of the 35 cylinder A are covered with a suitable amount of oil. The reciprocating movement of the piston B causes the oil ring E to catch the oil on the down or out stroke of the piston and convey it upward with the 40 return stroke, and distribute, or, in other words, suitably oil the cylinder walls.

The annular groove F below the oil ring E is a gathering groove and retains oil in a suitable manner to aid the operation of 45 the oiling ring E. The annular groove F' on the upper side of the oil ring E likewise gathers oil on the upper side of the oil ring E.

In practice it has been found that under 50 ordinary conditions on the suction stroke of an engine a considerable vacuum is formed at the head of the piston to draw in the gases. This vacuum is increased when the engine is throttled and amounts often to as 55 much as 20 inches of mercury. The effect is carrying the vacuum down along the walls

of the piston to the rings which exerts a tension on the oil film at the joint between the engine and the cylinder wall. Such tension causes the oil to flow in the thin film 60 past the ring and to the head of the piston, reaching the combustion chamber where it is carried away as smoke. On the other hand when the engine is working under full load, the suction is much reduced owing to 65 the throttle being opened, and the tension on the oil film therefore less. In order to make these conditions at the edge of the oil ring alike under all working conditions of the engine, I have placed the two oil 70 grooves, one above and the other below the oil ring, both connected with the interior of the piston, which space is always subject to crankcase pressure conditions. Thus the conditions on the oil film are always the 75 same no matter what conditions exist at the head of the piston. The effect of my invention is the equalizing of the pressure at all times at both sides of the oil ring. To effect this a hole or a number of holes, such 80 as G', are bored from the annular groove F' through the piston wall. These holes are made of such size and arrangement that they will permit the pressure existing in the crankcase and below the piston to communicate with the annular groove F' in the 85 same manner as it communicates with the annular groove F through the hole or holes G. By the addition of the holes G', in conjunction with the holes G, equalizing of 90 the pressure on both sides of the oil ring E is established, and the oiling of the cylinder walls by means of the oil ring E is consequently likewise subject to the pressure conditions in the crankcase. The effect is the 95 maintaining on either side of the oil ring E the crankcase conditions as to pressure, and this results in eliminating those troubles 100 which have become evident and very objectionable where the provisions above described do not exist.

As the application of my invention may be varied and modified to suit constructions of engines and particular conditions, or in view of other requirements, I do not limit 105 myself to the exact construction herein shown and described, but—

What I claim and desire to secure by Letters Patent is:

1. In an internal combustion engine, in 110 combination with a cylinder, piston and crankcase coöoperating to vary the atmos-

pheric pressure between the piston and the crankcase, a packing and oil ring on the piston, annular grooves above and below and contiguous to the main groove of said oil ring, a passage between the upper groove and the interior of the piston.

2. In combination, a piston for an internal combustion engine, packing rings, an oil ring at the inner end of said piston, an 10 open groove on the inner side of and contiguous to said oil ring and a passage or vent between said groove and the inner side of the piston, a recess in the outer surface of the piston between the oil ring and the head 15 of the piston, and a passage or vent between said recess and the inner side of the piston.

3. In combination in a piston for internal combustion engines, a packing ring, an oil ring, a groove in the surface of said piston 20 between and extending from the oil ring and the inner end of the piston, and a groove between the oil ring and the head of the piston and contiguous to the oil ring groove, vents between each of said grooves

and the interior of the piston whereby the 25 pressure conditions in the crankcase are maintained in both of said grooves.

4. In a piston, a main packing ring groove and adjacent and contiguous thereto a second open groove of lesser depth than 30 the main groove.

5. In a piston, a packing ring groove, open recesses laterally contiguous to said groove of lesser depth than the piston surface, for the purpose described. 35

6. In a piston, a groove, a secondary groove within the main groove, a packing ring in the secondary groove, whereby an open groove or recess is left between the edge of the packing ring and the edge of 40 the main groove for the purpose described.

This specification signed and witnessed this 5th day of February 1912.

EDWARD R. HEWITT.
